UNITED STATES PATENT OFFICE.

ARTHUR CECIL BUTLER, OF WOLLASTON, MASSACHUSETTS.

TENSION-REGULATOR FOR SPINNING OR TWISTING MACHINES.

SPECIFICATION forming part of Letters Patent No. 691,594, dated January 21, 1902.

Application filed February 15, 1901. Serial No. 47,430. (No model.)

To all whom it may concern:

Be it known that I, ARTHUR CECIL BUTLER, a subject of the King of Great Britain and Ireland, residing at Wollaston, in the county of Norfolk and State of Massachusetts, have invented a certain new and useful Tension Regulator or Governor for Spinning or Twisting Machines, of which the following is a specification, reference being had therein to the accompanying drawings.

The invention relates to a device in a spinning or twisting machine for regulating or governing the tension of the yarn as it passes from the delivery-rolls through the traveler 15 to the bobbin; and it has for its object to provide a simple and efficient means for producing said result.

According to the present invention I am enabled to produce a stronger and more elastic 20 yarn and a more uniformly-compact cop or bobbin than has heretofore been produced. Furthermore, by the use of my invention finer "counts" may be spun than have heretofore been spun and a bobbin of smaller diameter 25 used than has heretofore been used in machines of a similar character. In addition my invention prevents the "ballooning" of the yarn, either when "spinning" or "twisting."

The above-mentioned advantages and object of my invention will be more fully set forth and explained in the hereinafter-detailed description.

The invention consists, broadly, of a rotatable governor or regulator attachment for 35 spinning or twisting frames which is capable of an axial or "up-and-down" movement relatively to its shaft or axle under strain of the yarn, whereby the tension of the yarn may be regulated or governed.

The invention further consists of the novel 40 features of construction hereinafter set forth and described, and more particularly pointed out in the claims hereto appended.

Referring to the drawings, Figure 1 is a side 45 elevation of the preferred form of my invention. Fig. 2 is a plan view of the same. Fig. 3 is a plan of the under side, and Fig. 4 is a view of a vertical section. Fig. 5 is a view of a modification of my invention, and Fig. 6 50 is a plan view of the same.

Like letters refer to like parts throughout the several views.

a is the spindle, of ordinary construction, receiving the bobbin *b* and sustained by the upper end of the elongated bushing *c*, supported, as usual, in the bushing-rail of the frame.

d represents the yarn, *e* the traveler, *f* the ring, and *g* the movable ring-rail, all of ordinary and usual construction.

i is a revoluble disk. *k* is a hollow split spindle-engaging sleeve projecting from the under side of said disk, and *l* an upright shaft or axle extending from the upper side of said disk.

The parts *i*, *k*, and *l* are made of metal, preferably of steel.

m is a collar made of suitable material and detachably connected with the upper end of the shaft or axle *l*.

n is a revoluble or rotatable governor or regulator made, preferably, of steel and loosely mounted on the shaft or axle *l* and adapted to rise and fall upon said shaft under strain of the yarn—that is to say, the said governor *n* is capable of an axial or up-and-down movement relatively to its shaft or axle under strain of the yarn.

o denote guides or eyes on the governor or regulator, through one of which the yarn passes.

The above-mentioned device is detachably connected with the spindle, as illustrated in Figs. 1 to 4, inclusive, the hollow split sleeve *k* being constructed of a suitable size and having such a degree of resiliency that it will fit onto and be held firmly on the top of the spindle, or it may be detachably connected with the bobbin in the same manner that the modification is connected, as shown in Fig. 5.

The mode of operation of the above device in so far as it has not already been disclosed is as follows: The yarn passes from the delivery-rolls and thread-guide (not shown) through the guide *o*, thence over and upon the periphery or edge of the disk *i*, and thence through the traveler to the bobbin. When the spindle and bobbin are rotated, the disk *i* is also rotated, the pull of the yarn upon the traveler causing the latter to revolve upon the race of the ring. The governor or regulator *n* is also caused to revolve, and the strain or pressure of the yarn caused by reason of the edge of the rotating disk *i* being

in close contact with the yarn assists or aids the traveler in its rotary movement. When the spindle and bobbin are rotated at any rate of speed, the pull of the yarn causes the 5 governor or regulator *n* to rise, the edge or periphery of the disk *i* acting as a fulcrum. The greater the pull or strain of the yarn the higher the governor will rise on its axle *l*, and when the tension becomes slack for any reason 10 the governor will fall, the rising-and-falling movement or up-and-down movement occurring between the disk *i* and the collar *m*. It is obvious that by this means the tension on the yarn is constantly regulated and governed, and thereby an even tension on the 15 same is maintained, whereby a stronger and more elastic yarn and a more uniformly compact cop or bobbin are produced. Furthermore, the yarn by being held continually in 20 contact with the edge of the disk *i* (and the latter revolving with the spindle) imparts to the traveler a rotary motion quite apart or in addition to its being dragged around by the bobbin. Thus much of the strain upon 25 the yarn is relieved, and for this reason and the fact that the regulator or governor readily yields to any extra strain that would otherwise break the yarn finer counts may be spun and a bobbin of smaller diameter used.

30 In the spinning or twisting machines the yarn as it is being built up on the bobbin has a tendency to "balloon" at a point intermediate the traveler and the delivery-rolls. This tendency to balloon is obviated by my 35 device, for besides being held in against the disk the slack is taken up by the weight of the governor *n*, thus reducing the tendency to balloon to a minimum.

I believe that I am the first person to produce 40 a governor or regulator for regulating the tension and for maintaining an even tension upon the yarn and one that acts automatically under stress of the yarn.

Referring to the modification set forth in 45 Figs. 5 and 6, the disk *p* is the rotatable governor or regulator, made, preferably, of metal and loosely mounted on the axle *l*, likewise preferably made of metal and adapted to rise and fall or to move up and down on said 50 axle under strain of the yarn. This up-and-down movement takes place between the collar *m* and the rotatable ring *q*, made, preferably, of metal, which is loosely mounted upon the axle *l'* and rests upon the collar *m'*, secured to said axle. The ring *q* is provided 55 with the guides or clips *o* *o'*, through one of which the yarn passes. The lower portion of the axle *l'* terminates in the split sleeve *k'*, which is slightly tapered at the bottom and 60 of such a size and having such a degree of resiliency that it will fit into a recess in the top of the bobbin and be held firmly in frictional contact with the bobbin. The spindle is shown as projecting into the sleeve *k'*; but 65 it is not necessarily held by the latter. The mode of operation of this modification is substantially the same as that of my preferred

form of invention, except that the modification is shown as being detachably connected with the bobbin, although it might obviously 70 be detachably connected with the spindle, as in Fig. 1, and excepting that in the modification the governor-disk *p* and the ring *q* are both loosely mounted on their axle, whereas in my preferred form of invention only the 75 governor is loosely mounted upon its axle, the disk *i* forming a part of or being rigidly attached to the axle.

In the modification the yarn passes from the delivery-rolls and thread-guide (not 80 shown) over and upon the edge of the governor-disk *p*, thence through the guide *o'*, and thence through the traveler to the bobbin. In the modification the strain of the yarn when the spindle and bobbin are rotated 85 causes both the governor-disk *p* and the ring *q* to rotate and the governor-disk to rise and fall in precisely the same manner that the governor *n* rises and falls. The principle of the invention, however, in both forms thereof is substantially the same, as will be readily seen without further description.

Both forms of my invention being detachably connected either with the spindle or bobbin the latter may be easily removed from 95 the spindle whenever it becomes necessary to remove it.

What I claim, and desire to secure by Letters Patent, is—

1. An attachment for spinning or twisting 100 frames, comprising a shaft provided with means for attaching it to a revoluble body, and a governor or regulator, through which the yarn is passed to the bobbin, mounted upon said shaft loosely and capable of up-and-down movement on said shaft as the latter revolves, substantially as described.

2. An attachment for spinning or twisting frames, comprising a shaft, a split sleeve by 110 which said shaft is applicable to a revoluble body, and a governor or regulator, through which the yarn is passed to the bobbin, mounted upon said shaft loosely and capable of an up-and-down movement on said shaft as the latter revolves, substantially as described.

3. An attachment for spinning or twisting frames, comprising a disk, and a shaft rising therefrom and provided with means for attachment to a revoluble body, and a governor or regulator, through which the yarn is passed 120 to the bobbin, mounted upon said shaft loosely and capable of an up-and-down movement on said shaft as the latter revolves, substantially as described.

4. An attachment for spinning or twisting 125 frames, comprising a disk, a shaft rising therefrom and provided with means of application to a revoluble body, and a governor or regulator, through which the yarn is passed to the bobbin, mounted upon said shaft loosely between the disk and a stop on said shaft, and capable of an up-and-down movement on said shaft as the latter revolves, substantially as described.

5. An attachment for spinning or twisting frames, comprising a shaft provided with means by which it is capable of direct application to a revolute body so as to revolve therewith, and a yarn-tension governor or regulator mounted upon said shaft loosely, rotatable therewith and capable of an up-and-down movement upon it.

6. In a spinning or twisting frame, the combination of a rotatable disk, a hollow split sleeve projecting from the under side of said disk, an axle or shaft extending from the upper side of said disk, and a rotatable governor or regulator loosely mounted upon said shaft and adapted to rise and fall thereupon under strain of the yarn.

7. In a spinning or twisting frame, the combination of a rotatable disk, a hollow split sleeve projecting from the under side of said disk, an axle or shaft extending from the upper side of said disk, and a rotatable governor or regulator loosely mounted upon said shaft

and adapted to rise and fall thereupon under strain of the yarn and provided with a yarn clip or guide.

8. In a spinning or twisting frame, the combination of a rotatable disk, a hollow split sleeve projecting from the under side of said disk, an axle or shaft extending from the upper side of said disk, a rotatable governor or regulator loosely mounted and adapted to rise and fall thereupon under strain of the yarn and provided with a yarn clip or guide, and a detachable collar arranged upon the upper end of said axle or shaft to confine the said governor upon its shaft.

In witness whereof I have hereunto affixed my signature, this 13th day of February, 1901, in the presence of two witnesses.

ARTHUR CECIL BUTLER.
